VEHICLE LIFT

Arthur H. Yordi, Kenosha, Wis.

Application December 15, 1953, Serial No. 398,264

7 Claims. (Cl. 187—8.41)

This invention relates to a vehicle lift particularly adapted for use when repairing or lubricating a vehicle.

It is an object of the present invention to provide a vehicle lift having an elevated work platform which will allow mechanics to have full access to the upper part of the vehicle, when the vehicle is in its elevated or lifted position, as well as to the underneath part for effecting repair and lubricating operations.

It is another object of the invention to provide a vehicle lift wherein guard rails will be lifted with the vehicle by its hoist so as to have them out of the way when the vehicle is in its lifted position and to allow full access from an elevated platform to the vehicle and wherein the elevated platform will be guarded when the vehicle is lowered to the ground position and away from the elevated platform, the guard rails being available at a time when the vehicle is lowered to prevent the mechanic or others from falling from the elevated platform.

It is another object of the invention to provide in a vehicle lift structure an overhead suspension which can be elevated and from which the vehicle can be suspended by block and tackle means connected to the vehicle at the respective opposite ends thereof so that at least one end of the vehicle can be retained in an elevated position independently of wheel supporting tracks of the lift, added access being given the mechanic to the vehicle and without the interference of the tracks of the lift, and wherein the guard rails form a part of the overhead structure so as to then be elevated therewith to an out-of-way position when the vehicle is elevated by the lift.

Other objects of the invention are to provide a vehicle repair and lubrication lift structure having the above objects in mind which is of simple construction, inexpensive to manufacture, has a minimum number of parts, rugged and secure, of pleasing appearance, easy to operate, and convenient and efficient in operation.

For other objects and a better understanding of the invention, reference may be had to the following detailed description taken in connection with the accompanying drawing, in which:

Figure 1 is a front perspective view of a vehicle mounted on a hydraulic lift and the lift in its lowered position with the inner guard rails in place on the elevated platform and the upper structure being in its lowered position;

Fig. 2 is a side elevational view of the structure with the upper structure elevated and the vehicle in its raised position and connected to block and tackle means at one end, the inner guard rails being elevated with the upper structure and the vehicle so easy access can be had to the top of the vehicle from the elevated platform.

Referring now to the figures, 10 generally represents the standard hydraulic vehicle lifting hoist having spaced wheel supports 11 and 12 over which the vehicle wheels are driven to locate vehicle 13 upon the hoist 10. The respective tracks 11 and 12 have respectively upwardly extending inner guide rails 14 and 15. The tracks 11 and 12 are joined together by a transverse member 16 to which a hydraulic hoist cylinder device 17 is connected. Above the track hoist 10 and elevated from the ground is a U-shaped platform 19 held in a fixed manner and in its elevated position by six vertical supports 20, engaging with the outer edge of the platform and three such posts being longitudinally spaced from one another along each side of the platform. Each post 20 has a fixed guard rail support extending upwardly therefrom as indicated at 21 and between which extend fixed parallel spaced and vertically spaced guard rails 22 and 23. The front posts 20

2

have inwardly extending guard rail projections 24 to prevent an attendant from walking off the front end of the platform. Full length guard rails extend across the opposite end of the platform and between the two end 5 guide rails support 21 at that location.

In order to gain access to the platform, see Fig. 2, there is an opening 25 at the rear end of the platform with which steps 26 communicate. A rail 27 is disposed along one side of the opening 25 and a swing gate 28 is 10 located in front of the opening and adapted to bear against the rail 27. This guards the opening 25 to prevent the mechanic from falling therethrough while working on the top of the platform 19. A step ladder 29 can be left on the rear of the platform 19 for use when desired and can 15 be moved over the platform to different locations along the side of the car. On the ground floor a work bench 30 is shown lying in back of the stairs or steps 26, Fig. 2.

Movable relative to the platform and adapted to be 20 lifted by the track hoist device 10 is an overhanging structure indicated generally at 31. This structure comprises four depending supports 32, see Fig. 1, that are slideable through the platform and respectively through support bearings 33 which may be sleeve type as shown, on the top of the platform 19. These rods or support members 32 are 25 elevated by the track hoist device 10 as the hoist device is moved upwardly with the vehicle 13 to position the vehicle at an elevation adjacent the platform 19, as shown in Fig. 2. The vehicle 13 will have been driven on to the track hoist 10 in the usual manner and made secure thereon against rolling movement. The elevation of the track hoist takes upwardly the upper overhanging structure 31. This upper structure has curved tie members 35 and 36 joining pairs of supports 32 at the front end of the device and at the rear end respectively. An intermediate curved 30 member 37 is connected between the vertically movable rod members 32 by inner guide rails 38 and will be taken upwardly by the guide rails which interconnect the upper ends of the vertically movable rod members 32.

The curved members 35, 36 and 37 are joined together 40 by a longitudinally extending pulley track member 39 over which a pulley hoist device 40 can be adjusted to engage either the rear end of the vehicle or the forward end of the vehicle in the manner illustrated. This pulley hoist device has a hook 41 adapted to engage with the bumper of the vehicle or some other part thereof and when operated, will elevate the vehicle.

It will be seen that when the upper structure 31 has 45 been elevated the guard rails 38 have been taken upwardly, as shown in Fig. 2, so that the mechanic will have full access to the top of the vehicle and around the same when the vehicle has been lifted to the elevation of the platform 19.

When the vehicle is lowered by the track hoist device 50 10, the guard rails 38 will be lowered along with the structure 31 so as to be placed adjacent to the inner edge of the platform 19 to prevent the mechanic from falling through the opening.

When the track hoist is raised to elevate the vehicle, the inner guard rails 38 will be elevated above the platform 19 so that they are out of the way of the mechanic desiring to work on the vehicle from the platform. This makes it possible for two mechanics to work on the vehicle at same time, one from beneath and the other from above, with the mechanic working from below being in a standing 55 position which is more comfortable than lying on his back beneath the vehicle. When the vehicle is lowered, the inner guard rails 38 will be lowered to the level of the platform to completely enclose the platform with guard rails. The vertical rods 32 pass through the sleeve bearing members 33, which are secured to the top of the platform.

While various changes may be made in the detail construction, it shall be understood that such changes shall be within the spirit and scope of the present invention as defined by the appended claims.

What is claimed is:

1. A vehicle lift construction comprising a track hoist device adapted to receive a vehicle, an elevated platform having an opening therein through which the vehicle can be elevated, vertical supports for supporting the platform in its elevated position, outer guard rail means on the top of said platform, a vertically movable structure

having inner guard rail means adapted to surround the opening when said structure is in its lowered position, said vertically movable structure connected to the track hoist device to be lifted by the same to elevate the inner guard rails as the vehicle is elevated through the opening to a position at the level of the platform, whereby access can be had to the vehicle from above and beneath at the same time.

2. A vehicle lift construction as defined in claim 1, and said platform being of U-shape with access to the opening being through one end of the platform, the vehicle being movable onto the hoist at the open end of the platform, a set of steps communicating with the closed rear end of the platform, said rear end of the platform having an opening through which one traversing the steps may pass to gain access to the top of the platform.

3. A vehicle lift construction as defined in claim 1 and said vertically movable structure further including a plurality of vertical rod members, rod supporting bearings disposed on the top of the platform and adapted to respectively accommodate the respective vertical rods, overhanging tie members interconnecting the rods at the front and rear of the movable structure and a longitudinally extending tie member connecting mid-portions of the transverse tie members.

4. A vehicle lift device as defined in claim 3, and said inner guard rail means including an intermediate tie member and guard rails extending between the intermediate tie member and the forward and rearwardly extending rods, said intermediate tie member being engageable with the top of the platform when the vertically movable structure is in its lowered position, said intermediate tie mem-

ber being joined to the longitudinally extending tie member.

5. A vehicle lift construction as defined in claim 4, and said longitudinally extending tie member serving as a track, a pulley track hoist movable along said track and having a hook adapted to engage with part of the vehicle to thereby permit the vehicle to be elevated from one end thereof above the track hoist and platform.

6. A vehicle lift construction as defined in claim 1, and said outer guard rail means including short guard rails extending laterally inwardly over the forward ends of the platform to cooperate with the inner guard rail means when the inner guard rail means is lowered to its position on the top of the platform.

15 7. In combination a vehicle lift comprising a track hoist device adapted to receive a vehicle at a first floor level and operable to raise the vehicle above said first floor level, a platform floor having an opening therein through which the vehicle can be elevated, vertical supports for supporting the platform floor in an elevated position relative to said first floor level, a vertically movable structure having guard rail means adapted to surround the opening when said structure is in its lowered position, said vertically movable structure connected to the track hoist device to be lifted by the same to elevate

20 said guard rail means above said platform floor as the vehicle is elevated through the opening to a position at the level of said platform floor, whereby access can be had to the vehicle from above and beneath at the same time.
